UNITED STATES PATENT OFFICE.

EDWIN L. DODSON, OF COVINGTON, KENTUCKY.

AUTOMATIC COIN CONTROLLED DEVICE FOR PERMUTATION SAFE LOCKS OR THE LIKE.

1,379,335.

Specification of Letters Patent. Patented May 24, 1921.

Application filed March 26, 1917. Serial No. 157,467.

To all whom it may concern:

Be it known that I, EDWIN L. DODSON, a citizen of the United States of America, and a resident of Covington, in the county of 5 Kenton and State of Kentucky, have invented an Automatic Coin Controlled Device for Permutation Safe Locks or the like, of which the following is a specification.

This invention relates to permutation- 10 locks for safes and the like, and its object is to provide an auxiliary device that is adapted for use in connection with the dog of the lock-mechanism whereby said dog is held out of possible contact with the permutation-tumblers, (even though the latter are 15 set to the proper unlocking-combination,) until a coin or other controlling-device is used to automatically come into co-action with the driver-tumbler so as to release said 20 dog and to permit it to engage with the alined notches in the tumblers and whereby the retracting of the lock-bolts can then follow for the opening of the safe-door.

The details of structure, as well as operation, will be fully hereinafter described and then more particularly set out in the claims.

In the accompanying several sheets of drawings, Figure 1 is a perspective view of an ordinary fire-proof safe, showing a slot 30 or narrow opening in the closed door thereof for the insertion of the dog-releasing coin; Fig. 2, a fragmentary perspective view of the safe showing its door open in order to bring to view a record-card pocket or receptacle on the face of the removable cover- 35 plate or cap thereof, as well as a special lock used on the said cover-plate to prevent unauthorized access to the lock and coin-controlled mechanism, as well as coins accumu- 40 lated therein; Fig. 3, an interior elevation of a fragmentary portion of the safe-door showing the bolt-mechanism, the permutation-tumblers, and my improved coin-con- 45 trolled mechanism arranged in connection therewith and in the position all the devices assume when the tumbler-mechanism is in alinement ready for the bolt-mechanism to be drawn backward or retracted for the un- 50 locking of the door and at the time when the coin is to be dropped into the dog-controlling device ready for said dog to be released and to be dropped into engagement with the said alined tumblers; Fig. 4, a view 55 similar to Fig. 3, but omitting the bolt- mechanism and showing the permutation- tumblers in due alinement as well as in en-

gagement with the dog subsequent to the dropping of the coin through the chute or passage-way for engagement with the driver-tumbler and now ready for the bolts 60 to be drawn so as to open the door; Fig. 5, a transverse section of a fragmentary portion of the safe-door showing on its interior face a gravitating-dog (such as herein used to demonstrate my device,) and the slide-latch 65 mechanism used in connection with said dog for holding the latter up until released by a controlling-coin that is to be dropped through a chute in the safe-door, this view being taken on the dotted-line x, x , of Fig. 4, 70 but, also, on the same line in Fig. 3, but with the dog lowered instead of as in said Fig. 3; Fig. 6, a longitudinal section of the slide-latch and its support, showing the coin-chute and the latch controlling-spring, the 75 said slide-latch being in its retracted position, away from its supporting or detaining engagement with the dog; Fig. 7, a detail elevation of the driver-tumbler showing the manner in which its edge is raised or ele- 80 vated adjacent the dog-notch thereof, the purpose of which will be hereinafter clearly referred to; Fig. 8, a transverse section, partly in elevation, taken on the dotted-line y, y , of Fig. 3, showing the permutation- 85 tumblers, the operating knob therefor, the bolt-operating handle or lever, (as here used to demonstrate the device) and the coin chute leading to the latch device that is used for supporting the dog preparatory to 90 its engagement with the alined tumblers and ready for the controlling-coin; and Fig. 9, a perspective view of the lock-tumblers together with the fore end of the dog that is ready to be dropped into their notches when 95 duly alined.

1 indicates the safe-body; 2, the hinged door thereof; 3, the inner cap or cover-plate of the door, removably connected at 3^a at its lower edge and preferably provided with a special lock 4 at its upper edge, such lock being especially intended to prevent unauthorized access within; 5, the usual protrudable bolts of the door; 6, the vertical carrier-bar for said bolts 5; 7, the rear- 100 wardly-extending horizontal bar that is provided on said bolt carrier-bar and slidably-connected to the back-wall 8 of the lock-chamber 9 by means of screw 10, a slot 11 being provided in said bar 7 to allow for the 105 sliding-movement thereof and, in turn, the reciprocal-movement of the bolts 5 to lock

and unlock the door, such slot limiting said reciprocal-movements of said bolts; 13, the permutation-tumbler chamber; 13^a a semi-circular box having a hollow protuberant bearing 13^b and attaching-lugs 12, one, only, of the latter being shown in Figs. 3 and 4; 14, a series of permutation tumblers or idlers mounted, as customary, in the chamber 13 on the hollow bearing 13^b; and 15 a spindle or arbor that is controlled by an outer knob 16 carrying, as usual, the dial-plate 17.

A bolt-throwing lever or handle 18 is provided on said spindle or arbor 15 and is mounted at the outer end of a tube or sleeve 15^a that carries at its inner end a notched cam 16^a whereby the bolt-mechanism is suitably coupled to throw the latter when the said tumblers are in the proper combination-alinement.

The peculiar structure of combination-dial and bolt-throwing lever-mechanism, wherein both are concentrically-mounted within but a single hole in the safe-door is one of many forms that is already being used in the manufacture of safes but not essential, however, to the use of the coin-controlled mechanism that forms the material and essential feature of the invention herein, and which is intended to operate in connection with the dog and the driver-tumbler of the permutation device that is used in safes.

19 indicates the innermost or driver tumbler of the notched permutation-tumblers that are mounted on the spindle or arbor 15. This tumbler 19 is, therefore, not an idler or loose one, but it is duly keyed or otherwise coupled to the arbor so as to turn therewith in either direction, and an arm 40 or lever 20 is mounted on said arbor, adjacent the hub of the driver-tumbler 19, and has an outer rounded end.

Adjacent the notch 21 of the driver-tumbler 19 I provide the periphery or edge 45 with a rounded projection or hump 22, the purpose of which will be duly referred to and defined hereinafter.

23 indicates a gravitating arm, pivotally-mounted on a screw or bearing 24 at its thickened or oppositely bossed rear-end and having at its narrowed or thinned fore-end a transverse pendent portion or dog-member 25, the latter being adapted to enter the usual notches in the permutation-tumblers, 55 that include the driver-tumbler 19, when it is intended to retract or withdraw the bolts for unlocking the safe-door, as customary. The screw 24 passes through the bossed portion of the dog 25 into a boss 7^a 60 on the slotted rear portion of the horizontal bar 7 that extends rearwardly from the vertical bolt carrier bar 6.

A shoulder 26 is provided on the rear face of the dog-member 25, the purpose of 65 which I will presently describe.

27 indicates a horizontal block or bar attached by means of screws 28 to the upper face of the horizontal portion 29 of the lock-chamber 12. The fore-edge of this block 27 projects beyond the fore-edge of 70 said portion 29 of the lock-chamber and has a pendent, longitudinal dovetail-formation 30 made integral therewith. The said dovetail-formation 30 carries a corresponding dovetail-slide 31 which has a horizontal 75 slot 32 in its fore-end, the shank of a vertical screw-eye or the like 33 passing upwardly through said slot into the bottom of the block 27, as best shown in Fig. 6. At the extreme fore-end of said slide 31, just beyond 80 said slot 32, I provide a short, vertical, auxiliary chute-extension 34 whose upper end is slightly flared outwardly as shown at 35, and I further provide said chute-extension 34 at its rear with a lateral arm or extension 36, the latter having a nose 37 at its outer end and thereby completing the formation of a horizontal latch-arm, such nose-portion 37 thereof being adapted to engage the shoulder 26 on the dog-member 25, 90 as best shown in Fig. 3, whereby the dog is held elevated out of engagement with the aligned permutation-tumblers until it is released by means of a coin or the like 38 that is dropped into the said chute-extension 34 95 through a main chute or passage-way 39 that extends from the outer face of the front-wall 40 of the door 2 of the safe.

The main coin-chute 39 is attached by means of lugs 41 and screws 42 to the inner 100 face of the front-wall 40 of the door, as best shown in Fig. 3, and inclines downwardly from that point, the latter being somewhat above the horizontal plane of the lock-spindle, as best shown in Fig. 1, wherein 105 the mouth 43 of the coin-chute 39 is shown, such mouth 43 being simply a vertical narrow slit or slot for the accommodation of the desired coin that is permitted to freely pass therein.

A pair of duly spaced, ornamental designs 44 is produced on the face of the safe-door, to represent escutcheons of attractive outline, and in one of which the coin entrance-slot 43 is located, the other one having a 115 vertical heavy line 43^a produced therein in imitation of said entrance-slot 43, whereby both designs appear to the eye as being alike and thus disarming any suspicion by the safe tamperer of the presence of said 120 coin-slot or the necessity for the use of a coin in the safe-door to open the lock.

The lower or discharge end of the main coin-chute 39 is supported by the member 29 of the lock-chamber and has a pendent-arm 45 that is vertically-slotted at 45^a and, in turn, has a rearwardly-turned foot 46, as best shown in Fig. 6, the latter being intended for use in supporting the coin when in place in the auxiliary chute-extension 34 130

ready for the operation of the driver-tumbler 19 and the arm 20 when it is desired to unlock the safe and to open the door.

A spiral spring 47 is provided or stretched 5 between the screw-eye 33 and a hook 48, the latter being provided on the rear-end of the slide 31, as best shown in Fig. 6, in which view the chute-extension 34 and the latch-arm 36 are shown depressed or forced back- 10 ward as far as they will go longitudinally, or are intended to go, by means of the arm 20 that projects from the arbor of the driver-tumbler 19. The said spiral spring 47 is a retractile one and is shown under 15 expansion or tension in said Fig. 6, the reaction of the slide 31 and latch-arm 36 being caused by said spring 47 automatically as soon as the coin 38 is dropped or released from the chute-extension 34, subsequent to 20 the onward passage of the arm 20, which is the time for rotating the driver-tumbler and the retracting or withdrawal of the bolts in unlocking the safe.

49 indicates a coin tray or receptacle incased within the housing 50, the latter being a pendent portion of the lock-chamber 9, as best shown in Fig. 3. The said coin-receptacle flares at 51 at its upper end, into hopper-shape, to facilitate the entrance of 30 the coin as it drops from the chute-extension 34, after passing away from its foot-support 46. The coin-receptacle is a removable one so that the contents can be readily transferred from within the safe-door after 35 the cap or inner plate 3 has been unlocked at its upper edge so as to swing on the detents 3^a at its lower end forwardly, toward the operator, when the door is open.

A record-card receptacle 52 is provided on 40 the face of the cap or cover-plate 3, near its upper edge, adjacent the lock 4, as shown in Fig. 2, so that the desired account of the sums-total of coins removed from the coin-tray 49 can be conveniently kept therein and 45 readily referred to from time to time.

The projection or hump 22 adjacent the notch 21 of the driver-tumbler 19 is intended for use in positively elevating the outer end of the gravitating-arm 23 that carries the 50 dog-member 25 so that when that hump contacts with the lower edge of said dog-member 25 it raises the pivotal-arm 23 the desired distance for the positive engagement of the outer end or nose-portion 37 of the latch-arm 36 with the projection or shoulder 26 on said 55 dog-member when said latch-arm passes outwardly through the slot 45^a of the pendent-arm 45 of the coin-chute 39. The engagement of said latch-member with the dog-member in 60 supporting or detaining the latter normally out of or above contact with the peripheries of the tumblers is thus absolutely assured at the time when the door is closed and locked and, also, until a coin has been deposited 65 on the supporting-foot in the chute-extension

ready for the advancing contact of the outer end of the arbor-arm 20 in the operation of my device that I will now proceed to describe.

In the operation of the coin-controlled device that constitutes the essential feature of my invention herein, assuming that the door of the safe is locked, the desired coin, say a dime, is inserted in the entrance opening or slit 43 whence it descends through the main 70 chute or passage-way 39 into the auxiliary chute-extension 34, finding its first resting-place on the foot 46 of the pendent-arm 45. Prior to the insertion of said coin, however, the permutation or idler tumblers of the lock 75 are set in due alinement, ready for the engagement of the dog-member 25 with the alined notches of said idler-tumblers and the subsequent alinement of the driver-tumbler. 80

The really essential feature of my invention herein lies in the fact that the latch-arm 36 is in engagement with the shoulder 26 on the dog-member 25 so that said dog-member cannot engage with the alined 90 notches of the tumblers or, in fact, connect at all until said latch-arm 36 is withdrawn from said engagement with the said shoulder 26. To effect the disengagement of the said latch-arm 36 from upholding-contact with the dog-member, the arm or lever 20 on the tumbler shaft 15 is advanced forward (to the left, in Fig. 3,) so that its outer, rounded end contacts with the coin 38 that is resting on the foot 46 of the pendent chute-arm 45. 95 The movement of said arm 20 forces said coin away from the said supporting-foot 46 and it acts as a lever within the chute-extension 34 to depress or force the slide 31 backwardly into the position shown in Fig. 6. 100 At this time the outer dial indicates that the safe door can be opened. The outer handle 18 is now turned so that the arm 23 may swing downwardly with its integral dog-member 25 into engagement with the 105 alined notches of all the tumblers including the notch of the driver-tumbler. The retracting path of the bolt-carrying members being now open, the bolts 5 may be retracted by means of said handle 18, the tube 15^a, 110 the notched cam 16^a and the said dog-member 25 so that their outer beveled faces shall lie flush with that of the sloping face 6^a of the fore edge of the safe door, and the latter free to be swung open. When the coin 38 115 has reached the position shown in Fig. 6 and the arm 20 has further advanced with its arbor 15 in the rotation of the latter, the said coin drops from the chute-extension 34 into the tray 49 below, so that the door may be 120 swung open.

Access may now be had to said coin-receptacle at any time by the duly authorized person to receive such coin collections as may accumulate in the coin-receptacle by opening 125 130

the lock 4 and swinging the cap or cover-plate on its lower end outwardly. A record-card is intended to be kept in the receptacle 52 on the face of the cap or cover-plate 3 for convenience of said authorized person, or for others using the safe, to show the sums-total taken from the coin-receptacle from time to time in the use of the coin-controlled mechanism.

10 An additional and material object or advantage of said coin-controlled mechanism is to furnish an extra safeguard against opening the safe that is to be used in the sale of the safe on easy terms, the purchaser himself being compelled to put a coin of small convenient denomination in the door each time he actuates the lock thereof so as to enable him to open it and thereby practically forming an installment plan, as it were, in 20 which to pay for the safe.

I claim:

1. In a coin-controlled lock-mechanism for safe-doors, the combination of a lock-chamber, lock-bolts, a slotted rearwardly-extending bolt-bar, permutation-tumblers, a driver-tumbler, a pivotal-arm mounted on said slotted bolt-bar, a dog-member mounted at the fore-end of said pivotal-arm and adapted to engage the said tumblers, spring-latch 30 detaining means for said dog-member to prevent its engagement with the said tumblers until the latter are in due alinement, lock-operating means including an arbor or spindle, and coin-controlled means adapted 35 to be released for, in turn, releasing the dog-member when the inserted coin has reached in the lock-chamber and the said arbor or spindle turned, and then the said lock-operating means adapted to be actuated so that 40 said dog-member may drop into the notches of said tumblers for engagement therewith and then followed by the retraction of said lock-bolts, substantially as shown and described.

45 2. In a coin-controlled device for use in connection with the locks of safe-doors, the combination of a lock-chamber, lock-bolts, a slotted rearwardly-extending bolt-bar, notched permutation-tumblers adapted to be 50 brought into the desired alinement from outside the safe-door, a dial-spindle, a driver-tumbler rigidly mounted on the dial-spindle and having a peripheral notch therein, an arm projecting from said dial-spindle 55 and with its outer end of such length as to extend beyond the periphery of the said driver-tumbler, a pivotal-arm in the lock-chamber mounted on said slotted bolt-bar, a pendent dog-member provided on said pivotal-arm and adapted to engage the alined notches of the said permutation-tumblers including the notch of the driver-tumbler, a shoulder on said pendent dog-member, a coin-chute leading from the outer face of 60 the safe-door downwardly into the said lock- 65

chamber and with its discharge-end in vertical alinement above the circular path of movement of the said extended end of the said arm on the dial-spindle, a pendent arm provided at the said discharge-end of the coin-chute and having a lateral foot-extension, a reciprocally-moving slide under spring-tension and having at its fore-end a chute-extension the latter being adapted to be normally supported in alinement with the discharge-end of the main coin-chute and under said spring-tension, a latch-extension projecting forwardly from said chute-extension and with its extreme outer end adapted to engage the shoulder on said dog-member to detain the dog-member when normally out of engagement with the said tumblers, lock-operating means, and a coin-receptacle adapted to catch the coin when dropped from its first resting or landing place within the said chute-extension and upon the said lateral foot-extension when the said extended end of the arm on the dial-spindle has been brought into contact with the coin or other coupling-medium deposited in said chute-extension and whereby the said dog-member is automatically released for dropping into engagement with the alined notches of the tumblers ready for the lock-operating handle or lever of said lock-operating means that is used in manipulating the lock-bolts, substantially as shown and described.

3. In a coin-controlled device for use in connection with the locks of safe-doors, a lock-chamber, lock-bolts, a dial-spindle, notched permutation-tumblers, a driver-tumbler on the dial-spindle having adjacent its notch an outwardly-projecting hump-formation, an arm on the inner end of the dial-spindle, a slotted bolt-bar, a pivotal-arm in the lock-chamber mounted on the said slotted bolt-bar, a shouldered dog-member at the outer end of the said pivotal-arm, a coin-chute leading from the outer face of the safe-door to a discharge-point above the said driver-tumbler but to one side of vertical alinement with the arbor or spindle thereof, a pendent-foot at the discharge-end of said coin-chute, a dove-tail-formation 100 on the upper wall of the lock-chamber, a dovetail-slide mounted on said dovetail-formation on the lock-chamber and having a longitudinal slot therein, a vertical screw-eye whose shank engages the said dovetail-formation through the slot in the said dovetail-slide, a spring stretched between said screw-eye and a hook at the rear-end of said dovetail-slide to hold the latter normally under tension in its forward position, a vertical chute-extension at the fore-end of said dovetail-slide and adapted to be normally in alinement with the discharge-end of the coin-chute as well as in vertical alinement 105 above the foot-member below the said dis- 110

115

120

125

130

charge-end of the coin-chute, a coin-receptacle in the lock-chamber, a latch-extension projecting forwardly from said chute-extension and with its outer end adapted to engage the projection or shoulder on the dog-member for normally detaining the dog-member in the lock-chamber out of contact with the lock-tumblers until a coin or the like has been deposited in the coin-chute 5 and lands or rests within the chute-extension and upon the pendent-foot at the discharge-end of said coin-chute, the said coin being adapted to be frictionally-engaged by the outer end of the arm on the dial-spindle when the latter is actuated ready for the 15 throwing of the bolts and against the tension of said spring and such coin dropping into said coin-receptacle in the lock-chamber when the outer end of said arm on the dial-spindle has advanced from contacting-pressure therewith, and a cap or covering plate forming the inner wall of the safe-door and provided with a lock to prevent unauthorized opening thereof or unauthorized access to the coin-controlling and lock mechanism 20 within, substantially as shown and described. 25

EDWIN L. DODSON.
